SUSPENSION POST TRUSS

George E. France, Rte. 2, Box 60, Oswego, Ill. 60542

Filed May 17, 1971, Ser. No. 144,375

Term of patent 14 years

Int. Cl. D25—02; D30—02

U.S. Cl. D30—2

FIG. 1 is an elevation of the suspension post truss embodying my new design.

FIGS. 2, 3, and 4 are, respectively, top, side, and bottom views of the suspension post truss shown in FIG. 1.

FIG. 5 is a section taken along 5—5 in FIG. 1, enlarged in scale for convenience of illustration.

I claim:

The ornamental design for a suspension post truss, as shown.
